(57) **CLAIM**

I claim an ornamental design for a public access e-commerce facility, as shown and described.

DESCRIPTION

A kiosk providing facilities for multiple users at respective identical carrels.

FIG. 1 is a perspective view of the public access e-commerce facility showing my new design;

FIG. 2 is a front view thereof;

FIG. 3 is a top view thereof; and,

FIG. 4 is a front view of two of the carrels thereof.

The broken lines are shown in the views for illustrative purposes only and form no part of the claimed design.
